DAVID F. VAUGHAN AND DAVID L. VAUGHAN, OF RIVERTON, NEW JERSEY.

ANTICREEPER FOR RAILROAD-RAILS.

1,099,524.

Specification of Letters Patent.

Patented June 9, 1914.

Application filed December 16, 1913. Serial No. 803,361.

To all whom it may concern:

Be it known that we, DAVID F. VAUGHAN and DAVID L. VAUGHAN, citizens of the United States, residing at Riverton, in the county of Burlington and State of New Jersey, have invented certain new and useful Improvements in Anticreepers for Railroad-Rails, of which the following is a specification.

10 The object of our invention is to provide an anticreeper for railroad rails, of novel, simple and efficient construction having provision whereby it may be readily applied to or removed from a rail; whereby it will effectually prevent the creeping of a rail, and whereby, when applied to a rail, it will be always in constant readiness for action under all conditions.

The invention, as generally stated, consists 20 in the provision of a bar adapted to extend transversely beneath a rail base and having means on one end thereof adapted to engage the top of one side of a rail and adjustable means on the other end thereof and adapted 25 to engage the top of the other side of the rail base and operative to raise the end of the bar engaged therewith in a manner to clamp the anticreeper to the rail; the invention consists further in providing a novel stop 30 part clamped between the bar and the bottom of the rail and adapted to engage a stationary part of the road bed; the invention consists further in constructing the parts in a novel manner so that by operating 35 the said adjustable means the said bar may be sprung from a normal condition and thereby firmly grip the parts of the anticreeper to the rail in tending to resume said normal condition; and the invention consists 40 further in various novel features of construction and combinations of parts hereafter fully described and claimed.

In the accompanying drawings, illustrating 45 our invention: Figure 1, is a side elevation of a portion of a railroad, a portion of a cross tie and our improved anticreeper applied to the rail. Fig. 2, is an elevation of the parts shown in Fig. 1, as seen from a position looking at one end of the rail. Fig. 50 3, is a vertical section, on line 3—3 of Fig. 2. Fig. 4, is a bottom view of one of the rail engaging parts and the tie engaging part. Figs. 5 and 6 are views of the parts shown in Fig. 2, showing different positions of the parts of the anticreeper while being applied

to the rail in different ways. Figs. 7 and 8 are views showing different modifications of the invention.

Referring to the drawings, 2 designates a portion of a railroad cross tie and 4 a railroad rail of well known construction. The rail 4 rests upon the cross tie 2, as usual, and the rail base 5 has the usual upper inclined faces, as shown. The cross tie 2 forms a stationary part of the road bed which supports the rail 4 and over which the rail tends to creep under the well known conditions.

Our improved anticreeper is applied to the rail base 5 adjacent the cross tie 2, and in its preferred form of embodiment, is of the following construction: Extending transversely beneath the rail 4 is a bar 6 having a rail gripping part or hook 7 formed on one end thereof which embraces and extends over one side of the rail base 5. The other end of the bar 6 extends through and beyond an opening 8 in a rail gripping part 9 which is movable on the bar 6 and has a projection 10 extending over and engaging the top of one side of the rail base 5. The projecting end of the bar 6 is screw-threaded for the reception of a nut 11 between which and the rail gripping part 9 is interposed a split nut lock washer 12, as shown. It will thus be seen that, by tightening the nut 11, the rail gripping parts 7 and 9 may be forced toward each other in a manner to grip the sides of the rail base 5; and that the washer 12 will prevent accidental loosening of the nut 11.

The central portion of the bar 6 extends through a slot or opening 13 in a rib 14 formed on a stop part 15. This stop part 15 is arranged centrally beneath the rail 4 and has a flange or plate 16 adjacent the cross tie 2 and adapted to engage the cross tie and stop the movement of the rail when it starts to creep. The stop part 15 has a horizontal flange or plate 17 which is clamped between the top of the bar 6 and the bottom of the rail base 4; and the slot 13 is inclined downwardly toward the cross tie 2 forming a wedge 18 between the upper wall of the slot 13 and the upper face of the stop part 15. The wide end of the wedge 18 is between the bar 6 and the cross tie 2, so that if the bar 6 attempts to move with the rail 4 when it tends to creep, the wedge 18 will be forced between the bar 6 and rail 4 in a manner to separate the bar and rail 130

and thereby cause the stop part 15 to be more firmly clamped between the bar 6 and the rail 4.

In the construction shown in Fig. 7, the stop part 15 and rail gripping part 9 are formed independently of each other and are movable relatively to each other; and in the construction shown in Figs. 1 to 6, inclusive, the stop part 15 and rail gripping part 9 are connected by arms 19 formed integral therewith, the parts 9 and 15 and arms 19 being cast in a single piece.

The anticreeper may be applied to the rail 4 by first hooking the rail gripping part 7 over one side of the rail base 5 and placing the rail gripping part 9 in engagement with the other side of the rail base 5 but outwardly of the position it is to occupy later, as shown in Fig. 5, and then tightening the nut 11. When the parts are in the position shown in Fig. 5, the inner end of the projection 10 is in engagement with the top of the adjacent side of the rail base 5, the top of the bar 6 is engaging the bottom of the plate 17 and the top of the plate 17 is engaging the bottom of the rail 4. It will therefore be understood that as the nut 11 is tightened to bring the parts into the condition shown in Fig. 2, the projection 10 will ride up the inclined upper face of the rail base 5 and raise the adjacent end of the bar 6 and thereby firmly clamp the top plate 17 of the stop part 15 between the bar 6 and rail 4.

While not essential in every form of embodiment of our invention we preferably make the bar 6 of spring metal so that when the nut 11 is tightened to move the parts from the position shown in Fig. 5 to the position shown in Fig. 2, the bar 6 will be sprung from the normal condition shown in Fig. 5 and will assume the condition shown in Fig. 2, as the projection 10 rides up the inclined face of the rail base 5 and raises the adjacent end of the bar 6. Thus the bar 6 will, in tending to resume its normal condition, press the rail gripping parts 7 and 9 down firmly upon the rail base 5 and press the top plate 17 of the stop part 15 firmly up against the bottom of the rail 4. This is an important feature of our invention, as the spring action in the bar 6 will compensate for any irregularities between the different parts and will maintain all parts of the anticreeper in constant readiness for action at all times.

Instead of applying the anticreeper to the rail, as shown in Fig. 5, it may be applied as shown in Fig. 6, by first placing the rail gripping part 9 in its final position and placing the rail gripping part 7 in engagement with the rail base 5 but outwardly of the position it is to occupy later, as shown, and then tightening the nut 11. As the rail gripping part 7 rides up the inclined face

of the rail base 5, the end of the bar carrying the part 7 will be raised and the bar 6 will effect the gripping action as previously explained.

In Fig. 8, we have shown the lower face 20 of the rail gripping part 7 at a greater incline than the incline of the top of the rail base 5; therefore, as the nut 11 is tightened, the inclined face 20 cooperating with the top of the rail base 5, will enhance the upward movement of the adjacent end of the bar 6. This is an important feature in constructions where the inclined upper face of the rail base 5 is very near a horizontal plane and it is desired to raise one end of the bar 6 to a certain extent with a limited adjustment longitudinally of the bar.

By connecting the rail gripping part 9 and stop part 15 by the arms 19 the stop part 15 will be automatically moved to its proper position beneath the central portion of the rail 4 when the rail gripping part 9 is adjusted into clamping position; and the arms 19 will thereafter retain the stop part 15 in the desired central position.

The portion of the rib 14 forming the end of the slot 13 farthest from the cross tie 2 forms a back stop 21 between which and the cross tie 2 the bar 6 is located, so that the bar 6 may not move in a direction away from the cross tie 2 without carrying the stop part 15 with it. This is important, for the reason that the rail 4, to which the anticreeper is clamped, expands and contracts longitudinally under different weather conditions, and sometimes water is frozen in the ballast in the road bed, forming a mass between which and the tie 2 the plate 16 is located, and against which it is difficult to move the stop part 15. Thus the back stop 21 will insure the proper working relation of the bar 6 and stop part 15 under all conditions.

We claim:

1. The combination with a railroad rail having a base, and a stationary part of a road bed, of an anti-creeper adapted to engage said stationary part and comprising a spring bar extending beneath the rail and provided with a part engaging the bottom of the rail, the ends of said bar having rail gripping parts extending over the respective sides of the rail base, and means operative to force one rail gripping part toward the other, said bar being sprung from a normal condition and pressing said rail gripping parts downwardly and pressing said part engaging the bottom of the rail upwardly in tending to resume said normal condition.

2. The combination with a railroad rail having a base, and a stationary part of a road bed, of an anti-creeper adapted to engage said stationary part and comprising a spring bar extending beneath the rail and provided with a part engaging the bottom of the rail

the rail, one end of said bar having a rail gripping part extending over one side of the rail base, and a rail gripping part extending over the other side of the rail base and engaging said bar and removable therefrom, said bar being sprung from a normal condition and pressing said rail gripping parts downwardly and pressing said part engaging the bottom of the rail upwardly in tending to resume said normal condition.

3. The combination with a railroad rail having a base, and a stationary part of a road bed, of an anti-creeper adapted to engage said stationary part and comprising a spring bar extending beneath the rail and provided with a part engaging the bottom of the rail, one end of said bar having a rail gripping part extending over one side of the rail base, and a rail gripping part extending over the other side of the rail base and provided with means to adjust it relatively to said bar, said bar being sprung from a normal condition and pressing said rail gripping parts downwardly and pressing said part engaging the bottom of the rail upwardly in tending to resume said normal condition.

4. The combination with a railroad rail having a base, and a stationary part of a road bed, of an anti-creeper adapted to engage said stationary part and comprising a spring bar extending beneath the rail and provided with a part engaging the bottom of the rail, one end of said bar having a rail gripping part extending over one side of the rail base, and a rail gripping part extending over the other side of the rail base and having an opening therein into which said bar extends, said bar being sprung from a normal condition and pressing said rail gripping parts downwardly and pressing said part engaging the bottom of the rail upwardly in tending to resume said normal condition.

5. The combination with a railroad rail having a base, and a stationary part of a road bed, of an anti-creeper adapted to engage said stationary part and comprising a spring bar extending beneath the rail and provided with a part engaging the bottom of the rail, one end of said bar having a rail gripping part extending over one side of the rail base, a rail gripping part extending over the other side of the rail base and having an opening therein into which said bar extends, one of said rail gripping parts having an inclined face arranged at an angle with respect to the upper face of the adjacent side of the rail base, and means operative to force one rail gripping part toward the other and thereby cause said inclined face to ride over the rail base and raise one end of said bar and spring it from a normal condition and cause said bar to press said rail gripping parts downwardly and press said part en-

gaging the bottom of the rail upwardly in tending to resume said normal condition.

6. The combination with a railroad rail having a base, and a stationary part of a road bed, of an anticreeper adapted to engage said stationary part and comprising a spring bar extending beneath the rail and provided with a part engaging the bottom of the rail, one end of said bar having a rail gripping part extending over one side of the rail base, a rail gripping part extending over the other side of the rail base and having an opening therein, one end of said bar projecting through and beyond said opening and being screw threaded, and a nut screwed on to the projecting end of said bar, said bar being sprung from a normal condition and pressing said rail gripping parts downwardly and pressing said part engaging the bottom of the rail upwardly in tending to resume said normal condition.

7. The combination with a railroad rail having a base, and a stationary part of a road bed, of an anticreeper comprising a spring bar extending beneath the rail and having rail gripping parts extending over the respective sides of the rail base, a stop part adapted to engage said stationary part and clamped between said bar and the bottom of the rail, and means operative to force one rail gripping part toward the other, said bar being sprung from a normal condition and pressing said rail gripping parts downwardly and pressing said stop part upwardly in tending to resume said normal condition.

8. The combination with a railroad rail having a base, and a stationary part of a road bed, of an anticreeper comprising a spring bar extending beneath the rail and having a rail gripping part at one end thereof extending over one side of the rail base, a rail gripping part extending over the other side of the rail base and engaging said bar and removable therefrom, and a stop part adapted to engage said stationary part and clamped between said bar and the bottom of the rail, said bar being sprung from a normal condition and pressing said rail gripping parts downwardly and pressing said stop part upwardly in tending to resume said normal condition.

9. The combination with a railroad rail having a base, and a stationary part of a road bed, of an anticreeper comprising a spring bar extending beneath the rail and having a rail gripping part at one end thereof extending over one side of the rail base, a rail gripping part extending over the other side of the rail base and provided with means to adjust it relatively to said bar, and a stop part adapted to engage said stationary part and clamped between said bar and the bottom of the rail, said bar being sprung from a normal condition and pressing said

rail gripping parts downwardly and pressing said stop part upwardly in tending to resume said normal condition.

10. The combination with a railroad rail 5 having a base, and a stationary part of a road bed, of an anti-creeper comprising a spring bar extending beneath the rail and having a rail gripping part at one end thereof extending over one side of the rail 10 base, a rail gripping part extending over the other side of the rail base and having an opening therein into which said bar extends, and a stop part adapted to engage said stationary part and clamped between said bar and the bottom of the rail, said bar being sprung from a normal condition and pressing said rail gripping parts downwardly and pressing said stop part upwardly in tending to resume said normal condition.

11. The combination with a railroad rail having a base, and a stationary part of a road bed, of an anti-creeper comprising a spring bar extending beneath the rail and 25 having a rail gripping part at one end thereof extending over one side of the rail base, a rail gripping part extending over the other side of the rail base and having an opening therein into which said bar extends, a stop part adapted to engage said stationary part and clamped between said bar and the bottom of the rail, one of said rail gripping parts having an inclined face arranged at an angle with respect to the 30 upper face of the adjacent side of the rail base, and means operative to force one rail gripping part toward the other and thereby cause said inclined face to ride over the rail base and raise one end of said bar and cause it to spring said bar from a normal condition and cause said bar to press said rail gripping parts downwardly and press said stop part upwardly in tending to resume said normal condition.

12. The combination with a railroad rail having a base, and a stationary part of a road bed, of an anti-creeper comprising a spring bar extending beneath the rail and having a rail gripping part at one end thereof 45 extending over one side of the rail base, a rail gripping part extending over the other side of the rail base and having an opening therein, one end of said bar projecting through and beyond said opening and being screw threaded, a nut screwed on to the projecting end of said bar, and a stop part adapted to engage said stationary part and clamped between said bar and the bottom of the rail, said bar being sprung from 55 a normal condition and pressing said rail gripping parts downwardly and pressing said stop part upwardly in tending to resume said normal condition.

13. The combination with a railroad rail 60 having a base, and a stationary part of a

road bed, of an anti-creeper comprising a spring bar extending beneath the rail and having rail gripping parts extending over the respective sides of the rail base, and a stop part adapted to engage said stationary part and clamped between said bar and the bottom of the rail, said bar being sprung from a normal condition and pressing said rail gripping parts downwardly and pressing said stop part upwardly in tending to resume said normal condition.

14. The combination with a railroad rail having a base, and a stationary part of a road bed, of an anti-creeper comprising a spring bar extending beneath the rail and 80 having rail gripping parts extending over the respective sides of the rail base, and a stop part adapted to engage said stationary part and having a wedge formed thereon and clamped between said bar and the bottom of the rail, the wide end of said wedge being between said bar and said stationary part, said bar being sprung from a normal condition and pressing said rail gripping parts downwardly and pressing said stop part upwardly in tending to resume said normal condition.

15. The combination with a railroad rail having a base, and a stationary part of a road bed, of an anti-creeper comprising a spring bar extending beneath the rail and having rail gripping parts extending over the respective sides of the rail base, and a stop part adapted to engage said stationary part and clamped between said bar and the bottom of the rail, said stop part having a back stop adapted to be engaged by said bar and between which and said stationary part said bar is located, and said bar being sprung from a normal condition and pressing said rail gripping parts downwardly and pressing said stop part upwardly in tending to resume said normal condition.

16. The combination with a railroad rail having a base, and a stationary part of a road bed, of an anti-creeper comprising a spring bar extending beneath the rail and having rail gripping parts extending over the respective sides of the rail base, and a stop part adapted to engage said stationary part and having a wedge formed thereon and clamped between said bar and the bottom of the rail, the wide end of said wedge being between said bar and said stationary part, said stop part having a back stop adapted to be engaged by said bar and between which and said stationary part said bar is located, and said bar being sprung from a normal condition and pressing said rail gripping parts downwardly and pressing said stop part upwardly in tending to resume said normal condition.

17. The combination with a railroad rail having a base, and a stationary part of a road bed, of an anti-creeper comprising a

spring bar extending beneath the rail and having a rail gripping part at one end thereof of extending over one side of the rail base, a rail gripping part extending over the other side of the rail base and engaging said bar and removable therefrom, a stop part adapted to engage said stationary part and clamped between said bar and the bottom of the rail, and an arm integral with and connecting the removable rail gripping part and the stop part, said bar being sprung from a normal condition and pressing said rail gripping parts downwardly and pressing said stop part upwardly in tending to resume said normal condition.

18. The combination with a railroad rail having a base, and a stationary part of a road bed, of an anti-creeper comprising a spring bar extending beneath the rail and having a rail gripping part at one end thereof of extending over one side of the rail base, a rail gripping part extending over the other side of the rail base and having an opening therein, one end of said bar projecting through and beyond said opening and being screw threaded, a nut screwed on to the projecting end of said bar, a stop part adapted to engage said stationary part and clamped between said bar and the bottom of the rail, and an arm integral with and connecting the last named rail gripping part and the stop part, said bar being sprung from a normal condition and pressing said rail gripping parts downwardly and pressing said stop part upwardly in tending to resume said normal condition.

19. The combination with a railroad rail having a base, and a stationary part of a road bed, of an anti-creeper comprising a spring bar extending beneath the rail and having a rail gripping part at one end thereof of extending over one side of the rail base, a rail gripping part extending over the other side of the rail base and having an opening therein into which said bar extends, a stop part adapted to engage said stationary part and clamped between said bar and the bottom of the rail, and an arm integral with and connecting the last named rail gripping part and the stop part, said bar being sprung from a normal condition and pressing said rail gripping parts downwardly and pressing said stop part upwardly in tending to resume said normal condition.

20. The combination with a railroad rail having a base, and a stationary part of a road bed, of an anti-creeper comprising a spring bar extending beneath the rail and having a rail gripping part at one end thereof of extending over one side of the rail base, a rail gripping part extending over the other side of the rail base and having an opening therein into which said bar extends, a stop part adapted to engage said stationary part and clamped between said bar and the bottom of the rail, an arm integral with and connecting the last named rail gripping part and the stop part, one of said rail gripping

parts having an inclined face arranged at an angle with respect to the upper face of the adjacent side of the rail base, and means operative to force one rail gripping part toward the other and thereby cause said inclined face to ride over the rail base and raise one end of said bar and cause it to spring said bar from a normal condition and cause said bar to press said rail gripping parts downwardly and press said stop part upwardly in tending to resume said normal condition.

21. The combination with a railroad rail having a base, and a stationary part of a road bed, of an anti-creeper comprising a spring bar extending beneath the rail and having a rail gripping part at one end thereof of extending over one side of the rail base, a rail gripping part extending over the other side of the rail base and having an opening therein, one end of said bar projecting through and beyond said opening and being screw threaded, a nut screwed on to the projecting end of said bar, a stop part adapted to engage said stationary part and clamped between said bar and the bottom of the rail, and an arm integral with and connecting the last named rail gripping part and the stop part, said bar being sprung from a normal condition and pressing said rail gripping parts downwardly and pressing said stop part upwardly in tending to resume said normal condition.

22. The combination with a railroad rail having a base, and a stationary part of a road bed, of an anti-creeper adapted to engage said stationary part and comprising a spring bar extending beneath the rail and provided with a part engaging the bottom of the rail, one end of said bar having a part engaging the top of one side of the rail base, and means engaging the other end of the bar and the top of the other side of the rail base and operative to raise the adjacent end of the bar and spring said bar from a normal condition and cause said bar to resume said normal condition.

23. The combination with a railroad rail having a base, and a stationary part of a road bed, of an anti-creeper comprising a bar extending beneath the rail and having means at one end engaging the top of one side of the rail base, a stop part adapted to engage said stationary part and extending between the rail and said bar, and means engaging the other end of said bar and the top of the other side of the rail base and operative to raise the adjacent end of the bar and clamp said stop part between the bar and the rail.

24. The combination with a railroad rail having a base, and a stationary part of a road bed, of an anti-creeper comprising a bar extending beneath the rail and having means at one end engaging the top of one side of the rail base, a stop part adapted to

- engage said stationary part and extending between the rail and said bar, said stop part having a wedge formed thereon with its wide end between said bar and said stationary part, and means engaging the other end of said bar and the top of the other side of the rail base and operative to raise the adjacent end of the bar and clamp said stop part between the bar and the rail.
23. The combination with a railroad rail having a base, and a stationary part of a road bed, of an anticreeper comprising a bar extending beneath the rail and having means at one end engaging the top of one side of the rail base, a stop part adapted to engage said stationary part and extending between the rail and said bar, said stop part having a back stop adapted to be engaged by said bar and between which and said stationary part said bar is located, and means engaging the other end of said bar and the top of the other side of the rail base and operative to raise the adjacent end of the bar and clamp said stop part between the bar and the rail.
26. The combination with a railroad rail having a base, and a stationary part of a road bed, of an anti-creeper comprising a bar extending beneath the rail and having means at one end engaging the top of one side of the rail base, a stop part adapted to engage said stationary part and extending between the rail and said bar, said stop part having a wedge formed thereon with its wide end between said bar and said stationary part, and said stop part having a back stop adapted to be engaged by said bar and between which and said stationary part said bar is located, and means engaging the other end of said bar and the top of the other side of the rail base and operative to raise the adjacent end of the bar and clamp said stop part between the bar and the rail.
27. The combination with a railroad rail having a base, and a stationary part of a road bed, of an anti-creeper comprising a spring bar extending beneath the rail and having means at one end engaging the top of one side of the rail base, a stop part adapted to engage said stationary part and extending between the rail and said bar, and means engaging the other end of the bar and the top of the other side of the rail base and operative to raise the adjacent end of the bar and spring said bar from a normal condition and cause said bar to clamp said stop part in tending to resume said normal condition.
28. The combination with a railroad rail having a base, and a stationary part of a road bed, of an anti-creeper comprising a spring bar extending beneath the rail and having means at one end engaging the top of one side of the rail base, a stop part adapted to engage said stationary part and
- extending between the rail and said bar, said stop part having a wedge formed thereon with its wide end between said bar and said stationary part, and means engaging the other end of the bar and the top of the other side of the rail base and operative to raise the adjacent end of the bar and spring said bar from a normal condition and cause said bar to clamp said stop part in tending to resume said normal condition.
29. The combination with a railroad rail having a base, and a stationary part of a road bed, of an anti-creeper comprising a spring bar extending beneath the rail and having means at one end engaging the top of one side of the rail base, a stop part adapted to engage said stationary part and extending between the rail and said bar, said stop part having a back stop adapted to be engaged by said bar and between which and said stationary part said bar is located, and means engaging the other end of the bar and the top of the other side of the rail base and operative to raise the adjacent end of the bar and spring said bar from a normal condition and cause said bar to clamp said stop part in tending to resume a normal condition.
30. The combination with a railroad rail having a base, and a stationary part of a road bed, of an anti-creeper comprising a spring bar extending beneath the rail and having means at one end engaging the top of one side of the rail base, a stop part adapted to engage said stationary part and extending between the rail and said bar, said stop part having a wedge formed thereon with its wide end between said bar and said stationary part, and said stop part having a back stop adapted to be engaged by said bar and between which and said stationary part said bar is located, and means engaging the other end of the bar and the top of the other side of the rail base and operative to raise the adjacent end of the bar and spring said bar from a normal condition and cause said bar to clamp said stop part in tending to resume said normal condition.
31. The combination with a railroad rail having a base, and a stationary part of a road bed, of an anti-creeper adapted to engage said stationary part and comprising a bar extending beneath the rail and provided with a part engaging the bottom of the rail, one end of said bar having a rail gripping part extending over one side of the rail base, a rail gripping part extending over the other side of the rail base and having an opening therein into which said bar extends, one of said rail gripping parts having an inclined face arranged at an angle with respect to the upper face of the adjacent side of the rail base, and means operative to force one rail gripping part toward the other and

thereby cause said inclined face to ride over the rail base and raise one end of said bar and cause it to clamp the anticreeper to the rail.

32. The combination with a railroad rail having a base, and a stationary part of a road bed, of an anticreeper comprising a spring bar extending beneath the rail and having a rail gripping part at one end thereof extending over one side of the rail base, a rail gripping part extending over the other side of the rail base and having an opening therein into which said bar extends, a stop part adapted to engage said stationary part and extending between the rail and said bar, one of said rail gripping parts having an inclined face arranged at an angle with respect to the upper face of the adjacent side of the rail base, and means operative to force one rail gripping part toward the other and thereby cause said inclined face to ride over the rail base and raise one end of said bar and cause it to clamp said stop part against the bottom of the rail.

33. The combination with a railroad rail provided with a base having an inclined upper face, and a stationary part of a road bed, of an anticreeper adapted to engage said stationary part and comprising a spring bar extending beneath the rail and provided with a part engaging the bottom of the rail, one end of said bar having a rail gripping part extending over one side of the rail base, a rail gripping part extending over the other side of the rail base and engaging said inclined face and engaging the bottom of one end of said bar, and means operative to force one rail gripping part toward the other and thereby cause one rail gripping part to ride up said inclined face and raise one end of said bar and spring it from a normal condition and cause it to clamp said stop part between it and the rail in tending to resume said normal condition.

34. The combination with a railroad rail provided with a base having an inclined upper face, and a stationary part of a road bed, of an anticreeper adapted to engage said stationary part and comprising a bar extending beneath the rail and provided with a part engaging the bottom of the rail, one end of said bar having a rail gripping part extending over one side of the rail base, a rail gripping part extending over the other side

of the rail base and engaging said inclined face and engaging the bottom of one end of said bar, and means operative to force one rail gripping part toward the other and thereby cause one rail gripping part to ride up said inclined face and raise one end of said bar and force parts of the anticreeper into gripping engagement with the rail.

35. The combination with a railroad rail provided with a base having an inclined upper face, and a stationary part of a road bed, of an anticreeper comprising a spring bar extending beneath the rail and having a rail gripping part at one end thereof extending over one side of the rail base, a rail gripping part extending over the other side of the rail base and engaging said inclined face and engaging the bottom of one end of said bar, a stop part adapted to engage said stationary part and extending between the rail and said bar, and means operative to force one rail gripping part toward the other and thereby cause one rail gripping part to ride up said inclined face and raise one end of said bar and spring it from a normal condition and cause it to clamp said stop part between it and the rail in tending to resume said normal condition.

36. The combination with a railroad rail provided with a base having an inclined upper face, and a stationary part of a road bed, of an anticreeper comprising a spring bar extending beneath the rail and provided with a part engaging the bottom of the rail, one end of said bar having a rail gripping part extending over one side of the rail base, a rail gripping part extending over the other side of the rail base and engaging said inclined face and engaging the bottom of one end of said bar, a stop part adapted to engage said stationary part and extending between the rail and said bar, and means operative to force one rail gripping part toward the other and thereby cause one rail gripping part to ride up said inclined face and raise one end of said bar and clamp said stop part between it and the rail.

In testimony whereof we affix our signatures in presence of two witnesses.
